CLAIM

The ornamental design for an arm mechanism for a ski exerciser, as shown and described.

DESCRIPTION

FIG. 1 is a left front perspective view of the arm mechanism for a ski exerciser showing my new design;

FIG. 2 is a front elevational view thereof;

FIG. 3 is a left side elevational view thereof, with the arms in an alternate position;

FIG. 4 is a rear elevational view thereof;

FIG. 5 is a right side elevational view thereof, with the arms in an alternate position;

FIG. 6 is a top plan view thereof; and,

FIG. 7 is a bottom plan view.

The broken line showing of the base is for illustrative purposes only and forms no part of the claimed design.

FIG. 1

FIG. 2

FIG. 3

FIG. 4

FIG. 5

FIG. 6

FIG. 7
